Inventor:

Charles Nessler,
By Willie Fowler,
Attorney.

UNITED STATES PATENT OFFICE.

CHARLES NESSLER, OF LONDON, ENGLAND.

HAIR-CURLER.

1,105,595.

Specification of Letters Patent. Patented July 28, 1914.

Application filed June 7, 1913. Serial No. 772,334.

To all whom it may concern:

Be it known that I, CHARLES NESSLER, subject of the King of Great Britain and Ireland, residing at London, W., England, have 5 invented certain new and useful Improvements in Hair-Curlers, of which the following is a specification.

In processes for curling hair which embrace coiling a small portion of the hair 10 upon a metal curler and then applying lotion and heating or otherwise operating upon the hair, a form of curler has been employed which consists of a small metal tube about three inches long, preferably flattened at one 15 end and preferably having in its walls a number of small perforations. In use a small portion of hair about as thick as the curler is tied near the roots and also tied to the flattened end of the curler. It is then 20 coiled tightly around the curler from the flattened end (the end nearest the head) to the outer end, and there tied down upon the curler. Now in order to secure good waving of the hair it is necessary to coil the hair extremely 25 tightly upon the curler, which is difficult and which causes strain upon, and even injury to, the hands of the operator.

The present invention consists in an improved curler of this general type and 30 which after the hair has been coiled around it at a convenient tension, can be readily operated so as to tighten the hair upon itself to any desired degree; and it comprises a tube, a rod-like element within said tube 35 and projecting somewhat from the open end of said tube, and a ratchet and detent or equivalent connection between the tube and the rod-like element whereby each of said members may be rotated on the other in one 40 direction but not in the other.

In order that my invention may be readily understood I shall now describe, by way of a type or example, certain forms thereof and for that purpose I shall refer to the accompanying drawings in which,

Figure I is a side elevation of a complete curler. Fig. II is an end elevation thereof. Fig. III is a plan of Fig. I. Fig. IV is a view similar to Fig. I but with the tube partly in section so as to show the ratchet. Fig. V illustrates a modification. Fig. VI is an elevation partly in section showing another modification. Fig. VII is a cross section on the line *a*—*b* of Fig. VI. Fig. VIII is an 55 elevation partly in section of another form which is a slight modification of that shown

in Figs. VI and VII. Fig. IX is a cross section on the line *c*—*d* of Fig. VIII. Fig. X is a side elevation of a portion of the tube partly broken away to show the scoring of 60 the interior.

Referring now to Figs. I to IV inclusive, 1 is the curler consisting of a small metal tube flattened at one end, in this respect being similar to the known curlers hereinbefore referred to. At its open end 2 however it is provided with a longitudinal saw-cut 3 and two transverse saw-cuts 4, 5 so as to form two tongues 6, 7. These tongues 6, 7 are bent slightly inward as is seen more clearly 70 in Fig. II, and they engage in the teeth of a longitudinal pinion 8, slidably mounted in the end of the tube 1. Projecting from the end of the pinion are two flat tongues of metal 10, 10 spaced a short distance from 75 one another as shown.

The curler is used in the following manner: A small portion of hair is tied together near the head as hereinbefore mentioned. The string with which it is so tied 80 is then sprung into the space between the strips 10, 10 thus avoiding the necessity of tying. The hair is then coiled around the curler at a convenient tension from the end 2 toward the flattened end 11 and tied down 85 thereon. Now while the tongues 10 are held against movement, the other end 11 of the curler is turned in the direction of the arrow, the tongues 6, 7 acting as ratchet detents and riding over the teeth of the long ratchet 90 pinion 8. The holding and turning may be done by the fingers alone, but it is preferable to employ devices to give greater purchase than is possible with the fingers alone. Thus for example I may employ a slotted key to 95 engage the tongues 10, 10 and another key to engage the flattened end 11 of the tube, holding the former still and turning the latter in the direction of the arrow.

By means of my curler the hair may be 100 coiled very tightly and any uncoiling movement will be prevented by the engagement of the ratchet detents 6, 7 in the teeth of the ratchet pinion 8. In order to loosen the hair after the curling operation is completed, the 105 hair on the curler is grasped by the hand and given a backward twist in the usual way. The hair thus loosened the curler can be easily removed.

The form of curler described and illustrated is given by way of a type or example only and many modifications may be made

without departing from my invention. I have shown the detents as being formed by slotting the end of the tube itself and I find that this construction is simple and efficient and of low cost in manufacture.

5 In a modification which I illustrate in Fig. V I employ a tube having both ends flattened and this I divide into two parts at or about the middle of its length. Within 10 the open end of one half I rigidly fix a ratchet pinion 8* in such manner that it projects therefrom and is adapted to be inserted in the open end of the other half, this end being furnished with ratchet detents adapted 15 to engage the teeth of the ratchet pinion.

When I form the detent or detents by cutting the end of the tube itself, I prefer to construct the tube of steel. Further, any 20 convenient equivalent to a ratchet and detent device may be employed. Thus I may dispense with ratchet teeth on the rod-like element and in place of the detent I may employ a bent wire or wires carried by the 25 rod-like element in a plane perpendicular to the geometric axis of the tube and the free end or ends of which tend to spring out against the inner wall of the tube. I find that provided that the ends of the wire are pointed or have sharp edges they will catch 30 in the material of the tube and entirely prevent rotation of the rod-like element in one direction, while rotation in the other direction can take place readily. Such a construction is illustrated in Figs. VI and VII. 35 In these figures, 1 is the tube and 2 the rod-like element neither of these being provided with ratchet teeth. The element 2 has a groove at 11 and within this groove is a strong wire 12 which passes through a hole 40 15 in the turned down part 13 of the element 2. The ends of the wire are bent in opposite directions as shown and the engaging extremities 14 which in the drawing are shown as having sharp edges press firmly 45 outward against the inner wall of the tube 1. Rotation of the element 2 within the tube will be possible only in the direction shown by the arrow in Fig. VII.

In Figs. VIII and IX, I show a slight 50 modification of the construction illustrated in Figs. VI and VII. Here the wire 12 is given one or more turns around the turned down part 13 of the element 2 so that each of the engaging extremities 14 is in effect 55 at the end of a short helical spring and greater resiliency is attained.

In the construction shown in Figs. VI to 60 IX inclusive I may roughen the interior of the tube or score it longitudinally as indicated at 18 in Fig. X in order to give the extremities 14 of the wire a better hold. Or, in a further modification I might have more than two engaging extremities as will be readily understood.

65 Having thus described my invention what

I claim as new and desire to secure by Letters Patent is:—

1. A curler comprising the combination of a tube upon which the hair may be coiled and secured, a member projecting from the end of said tube and adapted to be held against rotation, the said tube and member being capable of relative rotary movement and means for permitting the one to be turned with respect to the other in one direction but not in the other. 70

2. A curler comprising the combination of a tube upon which the hair may be coiled and secured, a member projecting from the end of said tube and adapted to be held against rotation, the said tube and member being capable of relative rotary movement and a clutching device arranged between the two and permitting one to be turned with respect to the other in one direction but not 85 in the other. 80

3. A curler comprising the combination of a tube upon which the hair may be coiled and secured, a member projecting from the end of said tube and adapted to be held against rotation, the said tube and member being capable of relative rotary movement and a clutching device arranged between the two and comprising a resilient finger projecting from one of said parts and engaging with its end the other said part so as to engage it when moved in one direction but not in the other. 90 95

4. A curler comprising the combination of a tube upon which the hair may be coiled and secured, a rod-like member within said tube and projecting from one end thereof and adapted to be held against rotation, an engaging device mounted on said rod-like member and comprising a resilient wire 100 passed through said rod-like member and having its ends projecting therefrom and adapted to engage the interior of the tube 105 and permit relative rotary movement in one direction but not in the other. 110

5. A curler comprising the combination of a tube upon which the hair may be coiled and secured, a member projecting from the end of said tube and provided with a notch for receiving the binding cord near the 115 roots of the portion of hair to be curled to secure said member to the hair, the said tube and member being capable of relative rotary movement in one direction but not in the other, whereby the coiled hair on said tube may be tightened by the relative rotary movement of said tube and member. 120

6. A curler comprising the combination of a tube upon which the hair may be coiled and secured, a member projecting from the 125 end of said tube and provided with outwardly projecting tongues adapted to receive between them the binding cord near the roots of the portion of hair to be curled to secure said member to the hair, the said 130

- tube and member being capable of relative rotary movement in one direction but not in the other, whereby the coiled hair on said tube may be tightened by the relative rotary movement of said tube and member. 5
7. A curler comprising the combination of a tube upon which the hair may be coiled and secured, a member projecting from the end of said tube and adapted to be held against rotation, the said tube and member being capable of relative rotary movement in one direction but not in the other, the said tube being flattened at its outer end to provide a grip or handle. 10
- 15 8. A curler comprising the combination of a tube upon which the hair may be coiled and secured, a member projecting from one end of said tube and adapted to be held against rotation, the said tube and member being capable of relative rotary movement and means for permitting the one to be turned with respect to the other in one direction but not in the other, the said tube inclosing said means and being provided at the other end with a handle for grasping the tube. 20

rection but not in the other, the said tube being provided at the other end with a handle for grasping the tube. 25

9. A curler comprising the combination of a tube upon which the hair may be coiled and secured, a member projecting from one end of said tube and adapted to be held against rotation, the said tube and member being capable of relative rotary movement and means for permitting the one to be turned with respect to the other in one direction but not in the other, the said tube inclosing said means and being provided at the other end with a handle for grasping the tube. 30

In witness whereof I have signed my name to this specification in the presence of two subscribing witnesses.

CHARLES NESSLER.
